(57) **CLAIM**

An ornamental design for a bed mounted spreader assembly, as shown and described.

DESCRIPTION

FIG. 1 is a perspective view of a vehicle having a spreader assembly mounted in a bed of the vehicle and those lines shown in phantom form no part of the claimed invention; FIG. 2 is a perspective view of the spreader assembly; FIG. 3 is a side view of the spreader assembly; FIG. 4 is a top view of the spreader assembly; FIG. 5 is a rear view of the spreader assembly; and, FIG. 6 is a front view of the spreader assembly.

The broken line showing of a bed mounted spreader assembly is for illustrative purposes only and forms no part of the claimed design.
